UNITED STATES PATENT OFFICE.

EUGENE A. NELSON, OF NEW YORK, N. Y.

COMBINED PIPE WRENCH, CUTTER, AND DIE.

1,138,395.

Specification of Letters Patent.

Patented May 4, 1915.

Application filed December 15, 1914. Serial No. 877,325.

To all whom it may concern:

Be it known that I, EUGENE A. NELSON, a citizen of the United States, and a resident of the city of New York, borough of Manhattan, in the county and State of New York, have invented a new and Improved Combined Pipe Wrench, Cutter, and Die, of which the following is a full, clear, and exact description.

This invention relates to plumbers' and gasfitters' appliances, and has particular reference to an implement adapted especially for use upon the standpipes of gas mains in or along city streets. I do not wish, however, to be limited unnecessarily to any particular use or adaptation of the device constituting the subject matter of this invention.

More definitely stated, among the objects of the invention is to provide a tool or implement adapted to reach down into a casing beneath a pavement for the manipulation of a gas standpipe, the upper end of which is commonly located below the surface of the pavement within the casing.

The foregoing and other objects of the invention will hereinafter be more fully described and claimed and illustrated in the drawings forming a part of this specification in which like characters of reference indicate corresponding parts in all the views, and in which—

Figure 1 is a side elevation showing the adaptation of the implement to its work in a gas pipe casing and in the act of turning the nipple with respect to the main portion of the standpipe; Fig. 2 is a detail perspective view indicating the use of the device in extending the standpipe in accordance with the filling in or grading of the street; Fig. 3 shows the use of the device as a die; Fig. 4 is a vertical sectional view on a larger scale than Fig. 1 and showing the use of the implement as a wrench; Fig. 5 indicates the pipe cutter; Fig. 6 shows the anchor or gripping member in horizontal section; Fig. 7 shows the same in plan; and Fig. 8 is a horizontal section of the pipe wrench, the last four figures being substantially on the corresponding lines of Fig. 4.

The several parts of this device may be made of any suitable materials, and the relative sizes and proportions, as well as the general design of the mechanism, may be varied to a considerable extent without departing from the spirit of the invention herein-

after more fully described and specifically claimed.

Referring more particularly to the drawings, I show at 10 a casing secured beneath the pavement 11 and within which is arranged a standpipe 12 of a gas main. In the usual or old practice it is common for access to be had to the gas main through the standpipe at various points for the purpose of pumping accumulations of liquid or sediment from the main, and because of frequent usage or otherwise the threaded upper end of the standpipe soon becomes worn or damaged, rendering the standpipe useless and demanding renewal thereof. In the practice of my invention, however, I make use of a short section or nipple 13 connected to the main portion of the standpipe by a coupling 14. When, therefore, the upper end of the nipple becomes disabled, the nipple may be renewed at slight expense and trouble by unscrewing it directly from the coupling 14 and another nipple put in its place without disturbing the standpipe or requiring it to be renewed. This operation, however, must be performed below the pavement and within the casing 10; hence demanding that the implement or implements used be of such nature as to be insertible down into the casing and of a diameter smaller than the inner diameter of the casing.

As shown in the drawings, my implement comprises a head 15 having secured to the middle portion thereof a strong, upright, hollow stem 16 having any suitable form of handles 17 at its upper end. To the ends of the head 15 are pivoted a pair of jaws 18. The general direction or position of the jaws is parallel to each other and extending downwardly, but more specifically each jaw is provided with an inwardly directed angle 19 adjacent its pivoted end and hence providing for an outwardly and downwardly inclined cam portion between the angle and its lower free end. The jaws are made of heavy strong material and are preferably of rectangular form in cross section as indicated in Fig. 8, whereby the general strength of the jaws is increased and better facilities are provided for certain operations described below.

A follower 20 is mounted upon the cam portions of the jaws and is adapted to be moved along the same up or down between the angles and the lower ends of the jaws for

- the purpose of determining the position of the jaws with respect to each other. Said follower is provided with vertical holes 21 which have loose sliding fit upon the jaws.
- 5 The follower is pivotally connected to the lower end of a rod 22, said lower end being smooth and journaled loosely in the follower. A head 23 and nut 24 connected to the rod, however, prevent relative longitudinal movement between the rod and the follower. The main portion of the rod above the nut 24 is screw threaded in a central hole in the head 15, and the upper end of the rod 22 where it projects through and above the stem 16 is provided with a handle 25 of any suitable nature, whereby it may be rotated for the purpose of forcing the follower up or down with respect to the jaws and head 15.
- 20 After the follower is put in place upon the jaws and connected as indicated above to the operating members of the device, I connect to the lower ends of the jaws by any suitable means a pair of cutting wheels 26 and a pair 25 of rollers 27, the connections being made with the jaws through lag bolts 28 as shown herein. When the tool is in operating position, the cutters and rollers all lie in the same horizontal plane, but transverse to the 30 axis of the standpipe. It is frequently desirable to cut off the damaged upper end of a standpipe for the purpose of re-threading it and applying an extension, or for other purposes. The means just described 35 enables me to so cut and remove the upper end of the standpipe even though it may be located at a considerable distance below the surface of the pavement. To apply the implement to the pipe to be cut, it is projected 40 downwardly into the casing and the jaws are caused to straddle the end of the pipe as far as desired. By turning downwardly upon the handle 25 and rod 22, the follower 20 will act upon the jaws causing them to approach each other, bringing the cutting wheels 26 and rollers 27 into action upon the pipe. Then, by rotating the stem and head by the handles 17, the cutting wheels will 45 score the pipe and upon successive rotations of the rod 22, increasing the grip of the jaws upon the pipe, the pipe will be severed and the end removed.

I provide a gripping member consisting of a collar 29 large enough to slip over the coupling 14 and provided with an inwardly projecting flange at its upper end and shown as comprising a pair of semi-circular members 30 pivoted to the collar at 31. The purpose of this flange is to constitute a temporary holder for the collar 29 causing it to rest upon the coupling 14. The collar is provided with two pairs of set screws. One pair shown at 32 are adapted to be screwed outwardly radially so as to grip against the inner surface of the casing 10. The other

pair 33 are adapted to be turned inwardly to bind against the coupling as shown in Fig. 6. It will thus be seen that the main portion of the standpipe and coupling will be locked in positive position in the casing, 7 rendering it easy to treat the nipple portion of the pipe as desired. As shown in Fig. 2, the anchor member is holding the main portion of the standpipe and lowermost coupling, and the upper portion of the figure 7 indicates an auxiliary nipple or section put in place to lengthen the standpipe as may be required in the filling up of a street or the like. The two-part flange 30 makes it easy for the collar 29 to pass an upper coupling 8 so as to engage a lower coupling or to enable the anchor member to be removed from the casing after an upper coupling has been put in place in making the extension. The free ends of the flange members 30 may be locked 81 temporarily in place by set screws 34 acting through slotted ends of the flange members.

After the standpipe has been cut as above described, a new thread may be formed thereon by the use of a die 35 shown in Fig. 9c 3 as carried between the jaws and above the cutters and rollers. It will be understood that under ordinary conditions the holders or brackets 26' and 27' will not need to be removed from the lower ends of the 95 jaws. During the manipulation of the tool for the purpose of cutting the thread, the handles 17 will be turned to effect the cut and the handle 25 will be turned to lock the jaws firmly upon the die 35.

As shown best in Figs. 4 and 8, a pair of toothed blocks 36 are fitted to the free ends of the jaws 18 just above the brackets 26' and 27', these blocks having teeth or serrations adapted to grip the pipe or nipple to be screwed on or off of the main portion of the standpipe. The jaws or blocks 36 are of a size radially to grip the pipe or nipple without being interfered with by the cutting devices, and they are so shaped as to snugly fit the free ends of the jaws where they are locked temporarily by set screws 37. The teeth are so shaped as to grip the pipe when rotated in either direction.

I claim:

1. In an implement of the character set forth, the combination of a head, a pair of jaws pivoted to the ends of the head and extending downwardly, said jaws having downwardly and outwardly inclined portions, pipe engaging devices carried by the lower ends of the jaws, a follower slidably fitted to the jaws and movable along the inclined portions, means to rotate the head and jaws, and means to move the follower up or down along the jaws to cause the jaws to move away from or toward each other, said last mentioned means including a rod extending upwardly through the head and threaded therein, said rod being journaled 130

n the follower and rotatable independently of the means for rotating the head and jaws.

2. In an implement of the character set forth, the combination of a head, a stem extending upwardly therefrom, means to rotate the stem and head around a vertical axis, a pair of jaws connected at their upper ends to the ends of the head and extending downwardly therefrom, said jaws having divergent inclined portions below their connected ends, a follower mounted slidably upon the inclined portions of the jaws and snugly embracing the same, a threaded rod journaled at its lower end in said follower

between the jaws and having threaded connection with the head, and means to rotate the threaded rod independently of the rotation of the head and jaws whereby the position of the pivoted jaws is positively determined at all times. 15

In testimony whereof I have signed my name to this specification in the presence of two subscribing witnesses:

EUGENE A. NELSON.
